United States Patent [19]

Russell et al.

[11] Patent Number: Des. 303,922

[45] Date of Patent: ** Oct. 10, 1989

[54] HOUSINGS FOR LATCHES OR LOCKS

[75] Inventors: **Richard H. Russell**, Farmington;
David W. Kaiser, North Haven;
Richard M. O'Grady, Southington,
all of Conn.

[73] Assignee: **The Eastern Company**, Cleveland,
Ohio

[**] Term: **14 Years**

[21] Appl. No.: **72,282**

[22] Filed: **Jul. 10, 1987**

[52] U.S. Cl. **D8/321; D8/300;**
D8/313; D8/353; D8/331

[58] Field of Search **D8/300, 302, 306-308;**
D8/313, 322, 330-331, 336, 338, 346, 350, 353;
70/57, 63, 78, 84, 99, 101

CLAIM

The ornamental design for a housings for latches or locks, as shown and described. The ornamental design for a housings for latches or locks, as shown and described.

DESCRIPTION

FIG. 1 is a front perspective view of a housing for latches or locks showing our new design;
FIG. 2 is a front elevational view thereof;
FIG. 3 is a rear elevational view thereof;
FIG. 4 is a bottom plan view thereof;
FIG. 5 is a top plan view thereof;
FIG. 6 is a rear perspective view thereof;
FIG. 7 is a right side elevational view thereof;
FIG. 8 is a left side elevational view thereof;
FIG. 9 is a vertical cross-sectional view thereof, taken along line 9—9 of FIG. 2;
FIG. 10 is a vertical cross-sectional view thereof, taken along line 10—10 of FIG. 3;
FIG. 11 is a front perspective view of a second embodiment thereof;

FIG. 12 is a front elevational view of the embodiment of FIG. 11;
FIG. 13 is a rear elevational view of the embodiment of FIG. 11;
FIG. 14 is a bottom plan view of the embodiment of FIG. 11;
FIG. 15 is a top plan view of the embodiment of FIG. 11;
FIG. 16 is a front perspective view of a third embodiment thereof;
FIG. 17 is a front elevational view of the embodiment of FIG. 16;
FIG. 18 is a rear elevational view of the embodiment of FIG. 16;
FIG. 19 is a bottom plan view of the embodiment of FIG. 16;
FIG. 20 is a top plan view of the embodiment of FIG. 16;
FIG. 21 is a bottom perspective view of the embodiment of FIG. 16;
FIG. 22 is a right side elevational view of the embodiment of FIG. 16;
FIG. 23 is a left side elevational view of the embodiment of FIG. 16;
FIG. 24 is a vertical cross-sectional view of the embodiment of FIG. 16, taken along line 24—24 of FIG. 17;
FIG. 25 is a vertical cross-sectional view of the embodiment of FIG. 16, taken along line 25—25 of FIG. 18;
FIG. 26 is a front perspective view of a fourth embodiment thereof;
FIG. 27 is a front elevational view of the embodiment of FIG. 26;
FIG. 28 is a rear elevational view of the embodiment of FIG. 26;
FIG. 29 is a bottom plan view of the embodiment of FIG. 26;
FIG. 30 is a top plan view of the embodiment of FIG. 26;
FIG. 31 is a front perspective view of a fifth embodiment thereof;
FIG. 32 is a front elevational view of the embodiment of FIG. 31;
FIG. 33 is a rear elevational view of the embodiment of FIG. 31;
FIG. 34 is a bottom plan view of the embodiment of FIG. 31;

FIG. 35 is a top plan view of the embodiment of FIG. 31;

FIG. 36 is a rear perspective view of the embodiment of FIG. 31;

FIG. 37 is a front elevational view of a sixth embodiment thereof; the only difference from the embodiment of FIG. 31 being the inclusion of a hex tool receiving opening in the operator element;

FIG. 38 is a front elevational view of a seventh embodiment thereof, the only difference from the embodiment

of FIG. 31 being the inclusion of a key receiving opening in the operator element;

FIG. 39 is a front elevational view of eighth embodiment thereof, the only difference from the embodiment of FIG. 31 being the inclusion of a screwdriver receiving groove in the operator element;

FIG. 40 is a front perspective view of a ninth embodiment thereof; and

FIG. 41 is a front elevational view of the embodiment of FIG. 40 the rear, side, top and bottom being mirror images of those of the embodiment of FIG. 1.
